(57) **CLAIM**

The ornamental design for a accessory for holding goods, as shown and described.

DESCRIPTION

FIG. 1 is a perspective view of a accessory for holding goods showing an embodiment of the design of the invention.

FIG. 2 is a front view thereof.

FIG. 3 is a side view thereof.

FIG. 4 is a rear view thereof.

FIG. 5 is a top view thereof; and,

FIG. 6 is a bottom view thereof.

The broken line showing of environment on the drawings is included for the purpose of illustration only and forms no part of the claimed design.
